Assistant Examiner — Bryan N. Melvin

(57) **CLAIM**

The ornamental design for a cover plate for switches, as shown and described.

DESCRIPTION

The patent or application file contains at least one drawing executed in color. Copies of this patent or patent application publication with color drawing(s) will be provided by the Office upon request and payment of the necessary fee.

Cover plate for switches

1.1 : Perspective

1.2 : Front

1.3 : Back

1.4 : Top

1.5 : Bottom

1.6 : Right

1.7 : Left

The portions of the design shown in the color yellow are for the purpose of illustrating portions of the cover plate for switches that form no part of the claimed design.

1 Claim, 5 Drawing Sheets
